[57] **CLAIM**

The ornamental design for a food serving tray, as shown and described.

DESCRIPTION

FIG. 1 is a perspective view of a food serving tray showing my new design;

FIG. 2 is a top plan view thereof;

FIG. 3 is a side elevational view thereof; and

FIG. 4 is an end elevational view thereof.

The opposite end elevational view is a mirror image of FIG. 4.

The opposite side elevational view is a mirror image of FIG. 3.

The bottom plan view is a mirror image of FIG. 2, except for a minor unornamental difference in the dimensions of the circular elements shown and as can be seen in FIGS. 3 and 4.
